HEAT CONTROL TIME SWITCH

Bruno Loeffler, West New York, and John S. Pelan, North Plainfield, N. J., assignors to Mack Manufacturing Corporation, Long Island City, N. Y., a corporation of Delaware

Application December 1, 1939, Serial No. 307,120

3 Claims. (Cl. 200—34)

The present invention relates to control mechanism for switches and embodies, more specifically, a time control mechanism for heater circuit switches, particularly for circuits for controlling manifold heaters such as are used in certain internal combustion engines.

In the operation of engines such as Diesel engines, it is often desirable to heat the inlet manifold in order to facilitate starting. For this purpose, glow devices and other forms of mechanisms have been provided that have been connected in circuits energized upon energization of the starting motor circuit. The disadvantages of such heater systems are that, because they are always used in every starting operation, they place a load on the battery when it frequently is not necessary and also because the greatest effect of the heater is not felt until some little time after the heater and starting circuit is closed, thus needlessly energizing the starting motor before its effect can be advantageously used.

An object of the present invention is to provide a control mechanism by means of which a heater circuit may be controlled to utilize, efficiently, all power derived from the battery.

A further object of the invention is to provide a device of the above character by means of which the heater circuit may be closed in advance of the closing of the starting motor circuit.

Yet a further object of the invention is to provide a device of the above character by means of which the length of time of energization of the heater in advance of the starting motor may be controlled effectively.

Other and further objects of the invention will appear as it is described in connection with the accompanying drawings wherein:

Fig. 1 is a diagrammatic illustration of the wiring system used in connection with the present invention.

Fig. 2 is a view in section taken through the axis of a device constructed in accordance with the present invention.

Fig. 3 is a view in section taken on line 3—3 of Fig. 2 and looking in the direction of the arrows.

Fig. 4 is a rear view of the device of Fig. 2.

Fig. 5 is a front view of the device of Fig. 2.

Fig. 6 is a view showing a modified form of control member.

Referring to the above drawings and in particular to Fig. 1, a starting motor is shown at M and two batteries at A and B. The starting motor circuit is shown at 20, 21 and 22, a solenoid control switch at 23 and a starting switch at 24. A lighting circuit shown at 25 is connected to battery A and to a generator 26 for charging and lighting service.

Engine manifold heaters a, b, c, d, e and f are shown as connected in circuits with the batteries, heaters a, b and c being connected to bat-

tery A by wires A¹ and A² while heaters d, e and f are connected to battery B by wires B¹ and B². Solenoid switches are connected in each heater circuit and in a common control circuit 27, 28. 5 Wire 29 connects wire 27 to wire B² while wire 30 connects wire 28 to a stationary control contact 31 and wire 33 connects movable control contact 32 to wire B¹.

A second set of contacts 34, 36 are provided to prevent operation of the starting motor M under certain conditions. To this end, stationary contact 34 is connected to the solenoid control switch 23 by means of a wire 35 and movable contact 36 is connected to the starting switch 24 by a wire 37. 15 If desired, an auxiliary switch 36' may be connected across wires 35, 37 to permit manual control of the circuits.

A cam 38 is provided to control the contact arms 32 and 36, the cam being provided with a recess 39 to open contacts 31 and 32 and a recess 40 to control contacts 34 and 36. The mechanism for operating this cam 38 will now be described.

The cam 38 is mounted on a shaft 41 journaled in a casing 42. The casing is formed with a chamber 43 and provided with a cover 44 secured in position by bolts 45. Within the chamber and fitting snugly therein is a circular disc 46 keyed to the shaft 41 and formed with a slot 47 within which a vane 48 is slidably received. A spring 49 normally urges the vane outwardly and the vane is formed with a bleed port 50.

A plate 51 is mounted between the disc 46 and outer chamber wall and formed with a ball check 35 valve 52 which permits fluid to flow in a counter-clockwise direction as viewed in Fig. 3 but prevents fluid flow in the opposite direction. A suitable fluid such as oil is introduced into the chamber 43 and is used in a fashion presently to be described, to control the operation of the contacts.

Turning of the shaft 41 is accomplished manually by a plate 53 having a handle 54 and a pointer 55 that moves over a dial 56. A spring 57 is connected between the plate 53 and a boss 58 formed on the casing 42. This spring normally urges the plate and shaft into the "off" position shown in Fig. 5.

Upon the cover 44 is provided a plug 59 by means of which the chamber is filled with oil and the cover also carries the stationary contacts 31, 34 and the pivoted contacts 32, 36. Contact 32 is formed with a detent 60 adapted to ride on the surface of cam 38 and contact 36 is also formed with a detent 61 to engage the cam. A supplemental chamber 62 is provided to by-pass quickly the oil retarding return motion of the vane 48 in order that the movable contact 32 may break its circuit suddenly.

In operation, when the engine is to be started under conditions making desirable a heating of

the manifold, the handle is moved to turn the pointer 55 over the scale 56 to the point on the scale representing the time during which such heating is to be effected. During this motion, oil is drawn through the check valve 52.

The handle is then released and the oil between the valve 52 and vane 48 bleeds through the port 50 under the pressure of the spring 57.

Upon initial movement of the handle, the detent 60 rides out of the recess 39 and closes the contacts 31, 32 to energize the heater and the contacts remain closed until the vane reaches the auxiliary chamber 62, at which time the oil is suddenly by-passed and the contact 32 snaps open.

In order to prevent the needless operation of the starting motor when the required heating has not been effected, the recess 40 is formed to open contacts 34, 36 if more than a predetermined heating is required. The length of the recess 40 determines the extent of movement of the handle 54 permissible before the contacts 34, 36 are broken to open the starting motor circuit. Thus, if considerable heating is required, the handle 54 is moved to the desired point as before described and the starting switch may be closed, causing the starting motor to be energized automatically after the predetermined heating has been accomplished.

In the modification shown in Fig. 6, the plate 53 is moved so that the pointer 55 engages lug 70, regardless of the operating conditions existing from time to time. The fluid within the chamber 43 is selected so that its viscosity will vary with the temperature. For example, oil can be utilized and, inasmuch as its viscosity varies with its temperature, if the atmospheric conditions are such that little heating is required, the viscosity will be relatively low and the oil will pass freely through the restriction and permit the handle to be returned to the off-position with little delay, for example, say, 15 seconds. If, however, the atmospheric conditions are such that more heat is required for starting, the oil in the chamber 43 is cold and its viscosity relatively great. When the handle 54 is turned to the limit in a counterclockwise direction, the high viscosity of the oil will cause a greater time to elapse during the travel of the pointer 55 to the off position.

A further feature of this invention resides in the fact that the tension of spring 57 can be varied to vary the action of the spring and correspondingly, the bearing of the viscosity of the medium due to temperature changes upon the operating characteristics of the mechanisms.

It will thus be seen that only one motion is required to select and put in motion the desired heating operation and that this motion, after once being completed, insures that, after the predetermined period, the heater will be disconnected.

While the invention has been described with specific reference to the accompanying drawings, it is not to be limited save as defined by the appended claims.

We claim:

1. A switch mechanism comprising a casing having a substantially cylindrical chamber, an oscillatory member in, coaxial with and of less

diameter than said chamber forming an arcuate space therebetween for receiving a liquid, a vane projecting from said member across said space into sealing engagement with said casing, a check valve in said space permitting flow of liquid therethrough in one direction, resilient means for rotating said member in the opposite direction, means forming a passage for slow escape of liquid from between said check valve and said vane, means in the path of said vane forming a second passage for rapid escape of liquid around said vane as said vane approaches a normal position, a pair of switches movable into open and closed positions, and a cam movable with said oscillatory member for closing one of said switches and opening the other switch when said vane is out of said normal position and for opening said one switch and closing said other switch when said vane is in normal position.

2. A switch mechanism comprising a casing having a substantially cylindrical chamber, an oscillatory member in, coaxial with and of less diameter than said chamber forming an arcuate space therebetween for receiving a liquid, a check valve interposed between the ends of said arcuate space permitting flow of liquid therethrough in one direction, a vane projecting from said member into sealing engagement with said casing, resilient means urging said oscillatory member to rotate in a direction opposite to said one direction, a handle for rotating said member in said one direction, means forming a groove in an edge of said vane permitting liquid to leak slowly by said vane, a recess in said casing communicating with said space and of greater length than the width of said vane, permitting liquid to escape rapidly around said vane as the latter passes over said recess, a switch on said casing, and cam means connected to and oscillatable with said member for closing said switch upon rotation of said member by said handle in said one direction and opening said switch when said vane passes over said recess.

3. A switch mechanism comprising a casing having a substantially cylindrical chamber, an oscillatory member in, coaxial with and of less diameter than said chamber forming an arcuate space therebetween for receiving a liquid, a check valve interposed between the ends of said arcuate space permitting flow of liquid therethrough in one direction, a vane projecting from said member into sealing engagement with said casing, resilient means urging said oscillatory member to rotate in a direction opposite to said one direction, a handle for rotating said member in said one direction, a groove in an edge of said vane permitting liquid to leak slowly by said vane, a recess in said casing communicating with said space and of greater length than the width of said vane, permitting liquid to escape rapidly around said vane as the latter passes over said recess, a pair of switches on said casing, and cam means connected to and oscillatable with said member for closing one of said switches and opening the other upon rotation of said member in said one direction and opening said one switch and closing said other switch when said vane passes over said recess.
